US00D743097S

(12) **United States Design Patent**
Tucker et al.

(10) **Patent No.:** **US D743,097 S**
(45) **Date of Patent:** **** Nov. 10, 2015**

(54) **ELECTRONIC SMOKING ARTICLE**

- (71) Applicant: **Altria Client Services Inc.**, Richmond, VA (US)
- (72) Inventors: **Christopher S. Tucker**, Midlothian, VA (US); **Geoffrey Brandon Jordan**, Midlothian, VA (US); **Barry S. Smith**, Hopewell, VA (US); **Ali A. Rostami**, Glen Allen, VA (US)
- (73) Assignee: **ALTRIA CLIENT SERVICES LLC**, Richmond, VA (US)
- (**) Term: **14 Years**
- (21) Appl. No.: **29/511,925**
- (22) Filed: **Dec. 15, 2014**

Related U.S. Application Data

- (62) Division of application No. 29/469,741, filed on Oct. 14, 2013, now Pat. No. Des. 722,196, which is a division of application No. 29/443,134, filed on Jan. 14, 2013, now Pat. No. Des. 691,765.

CLAIM

The ornamental design for an electronic smoking article, as shown and described.

DESCRIPTION

FIG. 1 is a perspective view of an electronic smoking article showing our new design.

FIG. 2 is side elevational view thereof, the other side being a mirror image; and,

FIG. 3 is an end elevational view thereof.

The broken line showing illustrates portions of the electronic smoking article which form no part of the claimed design.
